UNITED STATES PATENT OFFICE.

ROBERT W. BLAISDELL, OF MILWAUKEE, WISCONSIN, ASSIGNOR OF ONE-HALF TO
FRED J. MAYER, OF MILWAUKEE, WISCONSIN.

SHOE-RELASTING MACHINE.

1,312,676.

Specification of Letters Patent.

Patented Aug. 12, 1919.

Application filed February 3, 1919. Serial No. 274,727.

To all whom it may concern:

Be it known that I, ROBERT W. BLAISDELL, a citizen of the United States, and resident of Milwaukee, in the county of Milwaukee, 5 and State of Wisconsin, have invented certain new and useful Improvements in Shoe-Relasting Machines; and I do hereby declare that the following is a full, clear, and exact description thereof.

10 My invention relates to new and useful improvements in means for lasting shoes, and it is more particularly directed to the provision of a machine for performing the second lasting operation on what is known as 15 turned shoes, such shoes being lasted and stitched inside out, and then turned and subjected to a second lasting operation to impart their final shape thereto.

It is primarily the object of my invention 20 to provide a machine whereby a shoe may be snugly fitted on the forward portion of the last in a most rapid and efficient manner, and without making unusual demands on the strength of the operator in contradistinction to the manual operation now employed of pounding the last against a table 25 or other support to effect a snug engagement of the shoe thereon.

A further object of my invention is to 30 provide a means for inserting a shoe on a last which does not require pounding of the last, with the consequent damage entailed thereby.

A still further object resides in the provision of a lasting machine adapted to perform the functions above set forth and which has its parts so arranged as to most readily receive a shoe and last for the operation of the machine, to procure economy of the operator's time and permit a most rapid operation of the machine.

With the above and other objects and advantages in view, which will be apparent as the description proceeds, my invention relates 45 in the novel features of construction, combination and arrangement of parts as hereinafter more particularly described and defined by the appended claims.

In the accompanying drawings:

50 Figure 1 is a side elevational view of a shoe relasting machine embodying my invention, portions of the structure being broken away.

Fig. 2 is a plan view of the machine.

55 Fig. 3 is a detail sectional view through

the movable jaw carrying member of the machine on a plane indicated by the line 3-3 of Fig. 1.

Referring now more particularly to the drawings, 5 designates a table or other support to which my machine is secured. The present embodiment of my invention includes a substantially U-shaped base plate 6 having apertures 7 in its intermediate portion for receiving screws or other fastening means for securing the plate to the edge portion of the table or other support, with the ends of the plate projecting beyond the support. A sole supporting post 8 rises from one end of the plate, carrying an upper head 65 having an inclined face 9 provided with a covering 10 of leather or other suitable sheathing material. A heel supporting post 11 rises from the other end of the plate and is provided with a recess 12 adapted to 70 snugly receive the heel portion of a last A, when the sole portion of the last rests on the inclined face 9. In Fig. 1 of the drawings, a turned shoe B is shown partially mounted on the forward portion of the last, the rear 75 end of the sole piece S of said shoe being loose as shown.

For drawing the shoe snugly onto the forward portion of the last, a channel bar 13 has one end portion pivoted to an inwardly extending lug 14 on the end of the base plate 6 adjacent the sole supporting post 8, the web portion of the bar being disposed upwardly and terminating in an upwardly extending fixed jaw 15. The sides of the bar are extended past this jaw to form pivot ears mounting a movable jaw 16 coöperating with the jaw 15 to clamp the rear end portion of the sole therebetween, the opposed 85 faces of the jaws being provided with serrations to afford a positive grip. An arm 17 extends from the movable jaw into the channel of the bar and is pivotally connected with a yoke 18 in which is threaded one end of a link 19 having its other end threaded in 90 a yoke 20 pivoted to the intermediate portion of a treadle lever 21, which has one end portion pivoted to a suitable frog bracket 22. The treadle is normally raised by a contractile spring 23 connected therewith 105 and with the table 5 or other support. The channel bar 13 constituting the movable jaw carrying member of my machine, is yieldably urged to raised position by a contractile coil spring 24 secured thereto and to the post 110

115

8, upward movement of the bar being adjustably limited by a screw 25 passed through an arm 26 upstanding on the pivoted end portion of the bar and engageable 5 with the post 8.

Thus, when a shoe is partially mounted on the last A, and the last placed on the supporting posts, with the rear portion of the sole piece of the shoe engaged between the 10 jaws 15 and 16, downward movement of the treadle 21 will first swing the jaw 16 toward the jaw 15 to exert a gripping action on the sole piece, and will then draw the sole piece downwardly and rearwardly, thus drawing 15 the forward portion of the shoe snugly onto the forward portion of the last, the completion of the lasting operation being effected by removing the last from the supports and drawing the heel portion of the last 20 from the heel portion of the shoe in the conventional manner.

My invention is particularly adapted for performing the second lasting operation on turned shoes, such shoes being first lasted 25 and stitched inside out, and then turned and subjected to the second lasting operation to effect the final shape of the shoe. Heretofore, it has been customary to mount the shoe upon the last, in the second lasting operation, by grasping the shoe, with the last partially inserted therein and then pounding the heel portion of the last against the table. This manual operation requires the 30 exercise of an unusual degree of strength on the part of the operator, thus requiring picked operators and in addition damages the heel portions of the lasts in a manner which materially impairs their usefulness and requires otherwise unnecessary replacements 35 from time to time.

My improved machine will effect the mounting of the shoe on the last in a most ready manner, without damaging the last whatever and without requiring the exercise 45 of an unusual degree of strength by reason of the leverage and foot action involved.

It is noted that when the bar 13 is raised by the spring 24, and the treadle is raised by the spring 23, the jaws are held in spread 50 relation whereby to facilitate the insertion of the heel piece of the shoe between said jaws as the last is seated on the supports, thus conducing to an exceeding rapid operation of the machine.

While I have shown and described a preferred embodiment of my invention, it will be understood that various changes and modifications of structure may be resorted to without departing in any manner from 55 the spirit of the invention, as defined by the appended claims.

What is claimed is:

1. A relasting machine including means 60 for affording stationary support for a last and means movable with respect to said sup-

port means and engageable with the sole of a shoe mounted on a last on said support means for drawing the shoe on the forward portion of the last.

2. A relasting machine including a last 70 support having a stationary abutment portion for the heel of a last, and movable means engageable with the sole of a shoe mounted on a last on said support for drawing the shoe on the forward portion of the 75 last.

3. A relasting machine including a last heel support, a last sole support, and means movable below said supports and engageable with the sole of a shoe mounted on a last 80 seated on said supports for drawing the shoe on the last.

4. A relasting machine including a base plate, spaced posts upstanding from the base plate, and adapted to seat the sole and heel portions of a last, a bar pivoted to the base plate, jaw members carried by said bar, and means for clamping said jaw members to a sole piece and drawing said bar downwardly to draw a shoe on a last seated on said posts. 90

5. A relasting machine including a base plate, spaced posts upstanding from the base plate and adapted to seat the sole and heel portions of a last, a bar pivoted to the base plate, means carried by said bar for engaging a sole piece, and means for rocking said bar to draw said sole piece. 95

6. A relasting machine including a pair of spaced supports, a bar pivoted below said supports, means resiliently urging said bar 100 upwardly, a relatively stationary jaw carried by said bar, a relatively movable jaw carried by said bar, an arm on the movable jaw engageable with the bar in open position of the movable jaw, a member connected 105 with said arm for closing the jaw and swinging the bar, and means for urging said member to hold the jaw in open position.

7. A relasting machine including a last support, a member mounted for movement 110 in a path longitudinal with respect to a last engaged on said support, a relatively stationary jaw on said movable member, a relatively movable jaw on said movable member and an actuating member connected with 115 the movable jaw to move said movable jaw toward the stationary jaw and to move said movable member.

8. A relasting machine including a last support, a member mounted for movement 120 in a path longitudinal with respect to a last engaged on said support, a relatively stationary jaw on said movable member, a relatively movable jaw on said movable member, an actuating member connected with the 125 movable jaw to move said movable jaw toward the stationary jaw and to move said movable member in one direction, and means yieldably urging said movable member in its other directions of movement. 130

9. A relasting machine including spaced supports for the sole and heel portion of a last adapted to mount the last in upwardly inclined position, an upwardly inclined bar pivoted between the supports adjacent the sole support, means carried by said bar for engaging the sole of a shoe mounted on a last on said supports, and means for swinging the bar downwardly to draw the shoe on the last.

10. A relasting machine including spaced supports for the sole and heel portions of a last adapted to mount the last in upwardly

inclined position, an upwardly inclined bar pivoted between the supports adjacent the sole support, means carried by said bar for engaging the sole of a shoe mounted on a last on said supports, a treadle movable under said supports and a link connecting said treadle and pivoted bar.

15
20
In testimony that I claim the foregoing I have hereunto set my hand at Milwaukee, in the county of Milwaukee and State of Wisconsin.

ROBERT W. BLAISDELL.
